METHOD AND APPARATUS FOR MIXING SOLID MATERIALS WITH LIQUIDS.

1,422,421.

Specification of Letters Patent.

Patented July 11, 1922.

Application filed August 21, 1920. Serial No. 405,198.

To all whom it may concern:

Be it known that I, ORIN D. CUNNINGHAM, a citizen of the United States, residing at Buffalo, in the county of Erie, State of New York, have invented certain new and useful Improvements in Methods and Apparatus for Mixing Solid Materials with Liquids; and I do hereby declare the following to be a full, clear, and exact description of the invention, such as will enable others skilled in the art to which it appertains to make and use the same.

This invention relates to an improved method and apparatus for mixing solid materials with liquids, and more particularly for mixing light powdered material with a heavy viscous liquid at a low temperature. The invention is of special value in effecting the mixture of a powdered material with a heavy viscous liquid such as concentrated sulfuric acid, where reaction takes place with evolution of heat, and where it is important to maintain a low temperature and vigorous agitation during the intermixture and reaction.

Where a solid material, in a powdered form, is to be added to a heavy liquid, such as concentrated sulfuric acid, and where it is important to maintain vigorous agitation of the mixture and sufficient cooling thereof to maintain a low temperature, and especially where the solid reacts with the liquid with the evolution of heat, it is difficult to obtain the necessary vigorous agitation combined with the necessary cooling effect. If brine coils are used for keeping the mixture cold, they inhibit the necessary vigorous agitation.

The present invention overcomes the difficulty of apparatus heretofore employed, in which an agitator and brine coils are provided in the same receptacle; and the present invention provides an improved agitation and cooling method and apparatus well adapted for bringing about the desired intimacy of intermixture of the solids with liquids, even where the solid is a light powder and the liquid a heavy viscous liquid, and for bringing about effective cooling of the mixture.

According to the present invention, the agitation and the cooling are effected in separate parts of the apparatus, which separate parts are so interconnected, and so coact, that the desired intermixture, agitation and

cooling will take place in a rapid and continuous manner.

The improved apparatus of the invention thus has a receptacle or reservoir provided with a cooling jacket and cooling coils for securing the necessary cooling effect, and a separate mixing and agitating compartment, to which the solid is supplied and in which vigorous agitation and admixture takes place; while the cooling and agitating compartments or receptacles are so connected that the agitated mixture is continuously forced into the cooling compartment, while the cooled liquid or mixture is continuously returned from the cooling compartment to the mixing compartment for further admixture of the solid material therewith.

The improved process of the invention involves the continuous admixture of the solid and liquid, the continuous discharge of the agitated mixture into the cooling compartment, with resulting cooling thereof to the desired degree, and the return of the cold mixture to the mixing and agitating compartment for the further addition and admixture of the solid material; so that the solid is progressively added and admixed, and the mixture continuously cooled, until the complete admixture and reaction has taken place.

The invention is applicable to the admixture and treatment of various materials, and especially the treatment of solid materials with concentrated sulfuric acid, where the solid materials react with the sulfuric acid with evolution of heat of reaction, and where it is important to maintain a low temperature during the admixture and reaction.

The invention will be further described in connection with the accompanying drawing illustrating one embodiment thereof in a somewhat conventional and diagrammatic manner. The nature and object of the invention, as well as its advantages, will more fully appear from the following more detailed description.

The apparatus illustrated in the accompanying drawing comprises a reservoir or receptacle 1 equipped with a brine coil or coils 2 and having a brine jacket 3. This reservoir or receptacle is adapted to contain the main body of the liquid, with which the solid is to be admixed. A separate chamber or compartment 4 is provided having therein a suitable agitator 5, shown as a V-shaped agi-

- tator closely fitting the sides of the cone-shaped bottom of the compartment. The compartment 4 has a cooling jacket 6 connected with the cooling jacket of the receptacle 1 by a connecting pipe 7. The brine or other cooling agent enters through the supply pipe 8, passes through the jacket 3, then through the pipe 7 to the jacket 6, and finally discharges through the pipe 9; or the flow of brine can be reversed, entering at 9 and leaving at 8. The mixing compartment 4 is connected with the compartment 1 by a large pipe 10 having a regulating valve 11 therein. The bottom of the mixing compartment 4 is connected with a centrifugal pump 12 which in turn is connected with the bottom of the compartment 1 through the pipe 13 and the branch pipe 14 having regulating valve 15 therein. The pipe 13 has an extension 16 having a regulating valve 17 therein, this extension being arranged to permit drawing off of the liquid mixture at the end of the mixing or reaction operation. It will be noted that the pipe 14 is connected with the receptacle 1 at a point remote from the pipe 10, so that the liquid mixture forced into the receptacle 1 through the pipe 14 will not pass directly to the outlet 10, but will serve to agitate the entire body of the liquid, owing to the velocity of its upward discharge. (A thermometer may be placed at any desired place in the apparatus, for example, in the pipe 13, as indicated at 18). The pipes 13, 14 and 16 are provided with a suitable insulation, such as magnesia mixture, to avoid undue warming of the mixture passing through these pipes. A deflector 19 is arranged at the outlet end of the pipe 10 to deflect the solution downward or to one side as it enters the receptacle or compartment 4. It will be understood that the apparatus is made of suitable acid-resistant material, where it is to be used with acid liquids, such as concentrated sulfuric acid. It will also be understood that the apparatus may be provided with suitable covers for closing it during operation, as well as suitable feeding devices (not shown) for supplying the liquid and the solid in the desired amount and at the proper rate. Where chemical reaction takes place in the apparatus, the material of the apparatus should, of course, be resistant to such chemical reaction.
- In the operation of the apparatus, the valves 11 and 15 are closed, the reservoir 1 is filled about two-thirds full with the viscous liquid to be used in the reaction, and brine or other cooling agent is supplied to the cooling jackets and cooling coils. The valves 11 and 15 are then opened, the centrifugal pump 12 is started, and the liquid in the reservoir 1 flows through the pipe 10 in amount regulated by the valve 11, into the chamber 4 by gravity. It then passes to the centrifugal pump 12 and is forced back into the reservoir 1 through the pipes 13 and 14. The rate of flow of the liquid is thus controlled by the valve 11 and the centrifugal pump 12, and the liquid is kept in constant circulation, owing to the gravity flow from the reservoir 1 to the mixing receptacle 4, and the action of the centrifugal pump in returning the liquid to the reservoir 1. The valve 15 will be kept wide open while the valve 11 will be so adjusted that the rate of flow of the liquid is properly regulated. The circulation of the liquid in the manner described results in rapid cooling, owing to the large cooling area provided by the cooling jackets and the cooling coil; and the liquid is thus rapidly brought to the desired low temperature.
- When the desired temperature is reached, the agitator 5 is started, the rate of flow of the liquid is readjusted so that the cone-shaped bottom of the mixing chamber 4 is partly filled in order to enable the agitator to form a vortex by rapid rotation of the solution, and the solid material is then slowly added to the chamber 4, becoming instantly mixed with the cooled liquid by the agitator. The rate of addition of the solid can be regulated to suit the conditions of the particular operation, and will depend upon various factors, such as the heat of reaction to be neutralized, the cooling effect desired, the rapidity of circulation, etc. The mixture formed in the compartment 4 is continually and rapidly transferred, after admixture, to the reservoir 1, entering through the pipe 15 with considerable velocity and thereby causing agitation of the liquid in the reservoir 1. The liquid or liquid mixture flows from this reservoir through the pipe 10 to the mixing compartment and the further amounts of solid are admixed therewith. This continuous circulation enables the solution to be thoroughly cooled before it enters the mixing chamber 4 to receive more solid material. Where the reaction takes place with the evolution of heat, the continuous and progressive character of the process enables the heat of reaction to be continuously and progressively neutralized, as the solid is progressively added, and the cooling and circulation progressively take place.
- When the admixture and reaction have been completed, the contents of the apparatus may be drawn off through the pipe 16.
- The method and apparatus of the invention are well adapted for carrying out exothermic reactions in sulfuric acid where the conditions of reaction require that the reacting substances be instantaneously mixed with the acid and the solution maintained at a low temperature. The solid may thus be of a character which combines with or dissolves in the acid so that the resulting mixture no longer contains the solid in a

solid state, but contains it in solution or in the form of reaction products. The present invention overcomes the difficulty involved in other types of apparatus, heretofore used 5 for similar purposes, in bringing about the proper mixing of very light solids with a heavy viscous liquid, inasmuch as the mixing and cooling operations of the present invention take place mainly in separate 10 chambers so connected that a rapid and continuous circulation from one to the other takes place.

It will be evident that the specific construction and arrangement of the apparatus 15 can be varied, and the mixing and cooling chambers differently arranged, or arranged in different relative positions, or connected with pipes having different relative positions, so long as continuity of operation and 20 of circulation is provided for. It will be evident also that the particular type and construction of the mixing chamber and of 25 the agitator is capable of variation without departing from the spirit and scope of the invention.

I claim:

1. The method of effecting the admixture 30 of solids with liquids at low temperatures, which comprises circulating the liquid from and to a cooling chamber through a mixing chamber of relatively small capacity, admixing the solid with the liquid in the mixing chamber with vigorous agitation and continuously returning the liquid with the ad- 35 mixed solid and reaction products to the cooling chamber, the rate of addition of the solid and the rate of circulation of the liquid being so regulated as to maintain the desired low temperature.

2. The method of effecting the admixture, 40 at a low temperature, of solids and liquids which react together with evolution of heat, which comprises gradually adding the solid to the liquid in a mixing chamber of relatively small capacity, continuously forcing the resulting mixture to a larger cooling chamber and subjecting it there to active cooling, and returning the cold liquid from the cooling chamber to the mixing chamber 45 for admixture of further amounts of solid therewith.

3. The method of effecting the admixture 50 of solids with liquids at low temperatures, which consists in continuously withdrawing a relatively small portion of liquid from a relatively large cooled body of liquid and in continuously returning such smaller portion to the larger body, and in mixing the solids with such portion during its passage from 55 and to the relatively large body, until complete admixture and reaction has taken place.

4. The method of effecting the admixture 60 of solids with liquids at low temperatures, which consists in continuously withdrawing

a relatively small portion of liquid from a relatively large cooled body of liquid and in continuously returning such smaller portion, and in mixing the solids with such portion during its passage from and to the relatively large body, until complete admixture and reaction has taken place, and in vigorously agitating such portion during the addition of the solids.

5. An apparatus for effecting the mixture 75 of solids with liquids at a low temperature, comprising a cooling compartment provided with cooling means, a mixing compartment for mixing the solids and liquids, and means for continuously withdrawing a relatively 80 small quantity of the liquid, passing it through the mixing compartment and returning it to the cooling compartment, until complete admixture and reaction has taken place.

6. An apparatus for effecting the mixture 85 of solids with liquids at a low temperature, comprising a cooling compartment provided with cooling means, a mixing compartment for mixing the solids and liquids, and means for continuously withdrawing a relatively 90 small quantity of the liquid, passing it through the mixing compartment and returning it to the cooling compartment until complete admixture and reaction has taken 95 place, and means within the mixing compartment for vigorously agitating the withdrawn portion as it passes through the compartment.

7. An apparatus for the instantaneous 100 mixing of light powdered material with viscous liquids maintained at a low temperature, comprising a cooling reservoir equipped with brine coils and containing the main body of the liquid, a mixing chamber into 105 which the liquid from the cooling reservoir flows by gravity, an agitator within the mixing chamber, and a centrifugal pump connected and arranged to transfer the mixture from the mixing chamber to the reservoir.

8. An apparatus for the instantaneous 110 mixing of light powdered materials with viscous liquids maintained at a low temperature, comprising a cooling reservoir having cooling coils and containing the main body 115 of the liquid, a cone-shaped mixing chamber into which the solution from the cooling reservoir flows by gravity, means for regulating such flow, an agitator within the mixing chamber which effects whirling of the 120 liquid with resulting production of a vortex, whereby the added solid material is instantaneously mixed with the liquid, and a centrifugal pump connected and arranged to transfer the resulting mixture from the mixing chamber back to the cooling reservoir.

9. An apparatus for the instantaneous 125 mixing of light powdered materials and viscous liquids maintained at a low temperature, comprising a cooling reservoir having 130

brine coils and adapted to contain the main body of the liquid, a mixing chamber into which the solution from the cooling reservoir flows by gravity, means for regulating such flow, an agitator in the mixing chamber for effecting substantially instantaneous admixture of solid with the liquid, and means for transferring the resulting mix-

ture again to the cooling reservoir, said means delivering at the bottom of the reservoir and at a point remote from the outlet to the mixing chamber, whereby the whole body of the liquid therein is kept in continual circulation. 10

In testimony whereof I affix my signature. 15
